14 Claims. (Cl. 250—36)

(Granted under the act of March 3, 1883, as
amended April 30, 1928; 370 O. G. 757)

My invention relates broadly to electron tube oscillator systems and more particularly to a power oscillator tube system having a high degree of frequency stability.

5 One of the objects of my invention is to provide a stabilized oscillation circuit including an electron tube having a cathode, control grid, inner anode and outer anode, with means for compensating for the effects of electrostatic capacity existing between the inner and outer anode elements.

Another object of my invention is to provide a circuit arrangement for an oscillation system employing an electron tube having a cathode, 15 a control grid, an inner anode and an outer anode, with an adjustable capacity connected between the control grid and outer anode elements of the tube and adjustable to apply an alternating potential to the outer anode which is substantially equal in amplitude and opposite in phase to that applied to the outer anode from the inner anode by virtue of the interelement capacity between the inner and outer anodes.

Still another object of my invention resides 25 in a circuit arrangement for interconnecting an oscillation circuit with a power amplification circuit where the oscillation circuit includes an electron tube having both inner and outer anodes with means for compensating for the undesirable coupling normally existent between the frequency determining portion of the circuit and the output circuit of the oscillator 30 terminating at the outer anode.

Other and further objects of my invention reside 35 in the circuit arrangement for a high frequency electron tube oscillator as set forth more fully in the specification hereinafter following by reference to the accompanying drawing in which:

40 Figure 1 shows a circuit arrangement for an electron tube oscillator controlled by a piezo electric crystal element embodying the principles of my invention; Fig. 2 shows a circuit arrangement embodying the principles of my invention and employing a resonant circuit 45 for determining the frequency of oscillation in the oscillation system; Fig. 3 shows a modified form of frequency control circuit arranged according to the principles of my invention and 50 employing a resonant circuit for determining the oscillation period of the system; Fig. 4 illustrates another modified form of oscillator circuit embodying the principles of my invention, the circuit being controlled by means of a piezo electric crystal element; and Fig. 5 illustrates 55

a manner of coupling an oscillator generator constructed in accordance with my invention to the input system of a power amplifier.

I have found in employing an electron tube having a cathode, a control grid, an inner anode and an outer anode in an oscillator system, that instability of the frequency arises due to the inherent electrostatic capacity existing between the inner and outer anodes of the tube. This electrostatic capacity results in undesirable coupling between the frequency determining portion of the circuit and the output circuit of the oscillation system. Changes in the loading condition of the output circuit are therefore felt in the frequency determining portion. I have found that the effect of this electrostatic capacity between the inner and outer anode elements is overcome and compensated by connecting a small variable capacity between the control grid and outer anode of the tube and suitably adjusting this capacity. Through the medium of this small variable capacity a radio frequency potential is applied to the outer anode which is equal in amplitude and opposite in phase to the potential which is applied to the outer anode by virtue of the electrostatic capacity between the inner and outer anodes. When this electrical condition is met, the radio frequency potential which exists across the impedance in the output circuit is due solely to the electron flow to the outer anode and better frequency stability is obtained.

Referring to the drawing in detail, the electron tube which is connected in the oscillation circuit is shown at 1, including the cathode 1a, the control grid 1b, the inner anode 1c and the outer anode 1d. The grid circuit 2 of the electron tube system includes the grid leak 4 extending between the control grid 1b and the cathode 1a. The output circuit is indicated at 3 extending between the outer anode 1d and the cathode 1a. The output circuit 3 includes the source of potential 7, connected between the cathode 1a and the anode 1d through impedance 9 across which the output from the oscillator may be derived. The cathode 1a is heated from the source 8. A connection is taken from the inner anode 1c to a point of positive potential at the source 7 through the impedance 6. A frequency control element such as an electro-mechanical vibrator, a mechanically vibratile element or a piezo electric crystal 10 is connected between the control grid 1b and the inner anode 1c for determining the oscillation frequency of the system. An adjustable condenser 11

11 is connected across the control grid 1b and the outer anode 1d and is variable to compensate for electrostatic capacity existing between the inner anode 1b and the outer anode 1d.

5 In Fig. 2, I have shown a resonant circuit 12 including an inductance 15 shunted by a variable condenser 14 and providing means for determining the oscillation period of the system. In the circuit shown in Fig. 2, a blocking condenser 16 is provided for keeping the positive inner anode potential off the control grid 1b. The adjustable condenser 11 connects between control grid 1b and outer anode 1d for compensating for capacity effects between the inner 10 and outer anodes. The other portions of the circuit in Fig. 2 are similar to the circuit arrangement of Fig. 1.

In Fig. 3, I have illustrated a modified arrangement of oscillator circuit wherein the impedance 6 is eliminated from the circuit, thus simplifying the circuit without sacrifice of the performance of the system. In this arrangement a tap 34 is taken from a potential nodal point on inductance 15 to a point 35 on potential source 7. The variable condenser 11 serves to neutralize the effect of the capacity between the inner anode 1c and outer anode 1d.

In Fig. 4, a crystal controlled master oscillator circuit has been shown wherein the generic impedances 6 and 9 have been replaced by the inductance 22 and the tuned circuit 17. The lower end of the inductance 22 connects to a point of positive potential on source 7 and the upper end of the inductance 22 connects to the inner anode 1c and to one side of the piezo electric crystal element 10. The piezo electric crystal element 10 is connected in series with condenser 16 to the control grid 1b as shown thereby preventing any possibility of the impression of positive potential on control grid 1b from the inner anode 1c. A resonant circuit 17 including an inductance 19 shunted by a variable condenser 18 connects in series between anode 1d and cathode 1a through the high potential source 7. The condenser 11 is adjustable for compensating for inter-electrode capacities in the manner explained in connection with Figs. 1, 2 and 3. Battery 8 supplies cathode heating potential to the cathode 1a. A negative bias is placed upon control grid 1b from battery 5. A high frequency by-pass condenser 21 connects around the high potential source 7 in the plate circuit. Leads are taken as represented at 36 from the output circuit of the oscillator through condenser 20 for feeding any desired amplification system.

In Fig. 5, I have illustrated a method of connecting an oscillation circuit to the input of a power amplifier with means for compensating for capacity effects between the inner and outer anodes. The power amplifier tube has been shown at 24 having an input circuit 28 and an output circuit 29, the input circuit being biased through impedance 26 from battery 27. A blocking condenser 25 is connected between the output of the oscillator tube 1 and the input circuit of the power amplifier tube 24 for isolating the amplifier grid 24b and the variable capacity 11 from the high voltage source 7. This blocking capacity 25 is very important in high voltage circuits especially when the variable condenser 11 might suffer a voltage breakdown which would place a high positive potential on the control grid 1b of the oscillator tube 1. The generic impedances 6 and 9 have been replaced by the

inductances 22 and 23. The input circuit 28 of the amplifier is connected across the output inductance 23 of the oscillator circuit. The cathode of tube 24 may be heated from a suitable source 33. Suitable by-pass condensers 31 and 32 are provided in the different portions of the amplifier circuit. The output circuit 29 contains a resonant system 30 from which tap connections extend to the succeeding amplification stage or transmission circuit. The variable capacity 11 is adjusted for compensating for the electrostatic capacity effects between the inner and outer anodes 1c and 1d of the oscillator tube 1.

I have found the circuit arrangement of my invention highly efficient in its operation and stable in maintenance of constant frequency oscillations.

While I have described my invention in certain preferred embodiments, I desire that it be understood that modifications may be made and that no limitations upon my invention are intended other than are imposed by the scope of the appended claims.
